HOLDER FOR RESERVE TOILET TISSUE ROLL

Jerome C. Turro, 245 Rumsey Road, Yonkers, N.Y.

Filed July 29, 1965, Ser. No. 86,353

Term of patent 14 years

(Cl. D4—3)

FIG. 1

FIG. 2

FIG. 3

FIG. 4

FIG. 6

FIG. 5

FIG. 1 is a perspective view of a holder for a reserve toilet tissue roll embodying my new design with the reserve roll of toilet tissue being shown in phantom lines, for illustrative purposes only;

FIG. 2 is a rear elevational view of the device of FIG. 1, with the two portions thereof in position telescoped toward each other;

FIG. 3 is a front elevational view of the device of FIG. 1;

FIG. 4 is an end elevational view from one end thereof; FIG. 5 is a top view thereof; and FIG. 6 is a bottom view thereof.

I claim:

The ornamental design for a holder for reserve toilet tissue roll, as shown and described.
